UNITED STATES PATENT OFFICE

WARREN S. SHERMAN, OF OKLAHOMA CITY, OKLAHOMA

STREET MARKER

Application filed March 8, 1928. Serial No. 260,175.

This invention relates to improvements in street markers.

The primary object of this invention is the provision of an improved street marker and mould for making and assembling the same; the improved street marker being adaptable for placement in concrete curbing, walls, and the like, and comprising color contrasted letters and framing, of cementitious material, assembled in a secure and novel relation.

Other objects and advantages of this invention will be apparent during the course of the following detailed description.

15 In the accompanying drawings,

Figure 1 is a perspective view showing the application of the improved street marker or main plate to cementitious curbing, at a street intersection.

20 Figure 2 is a vertical sectional view taken through the marker showing the construction thereof.

Figure 3 is a view of a mold, used for pre-casting letters adapted to be used in a street 25 marker.

Figure 4 is a transverse sectional view taken through the metal mold of Figure 3, showing the cementitious pre-cast letter therein.

30 Figure 5 is a vertical sectional view taken through the mold of Figure 3.

Figure 6 is a fragmentary longitudinal sectional view taken through a mold used to cast the cementitious frame, showing the 35 means for holding the pre-cast letters formed as shown in Figures 3 to 5 inclusive, during the pouring in the mold of Figure 6, of the cementitious frame forming material.

Figure 7 is a fragmentary longitudinal 40 sectional view taken through a mold used to pre-cast a cementitious slab or frame, according to this invention, using pattern letters which are withdrawn from the precast slab to leave pockets or recesses which are later 45 filled with the contrasting cementitious material poured into the pockets of the mold.

Figure 8 is the mold of Figure 7, showing the pattern letters in position after the pouring of the slab cement.

50 Figure 9 is a view of the mold of Figure

7, with the slab cement in place and the pattern letters withdrawn, leaving the pocket voids of the letters.

Figure 10 is a view of the mold of Figure 7, with the slab frame pockets filled with 55 letter forming contrasting cementitious material.

In the drawings, the preferred and modified forms of the invention are illustrative of the thought that the structure of the improved marker may be made in various ways. However constructed, it is preferred that the improved marker, designated by A in Figure 1 of the drawings, comprise a plurality of letters B, permanently and immovably held 60 within a preferably cementitious frame or slab C; the latter in turn being permanently and rigidly secured in a pocketed relation within a preferably cement wall or curb D.

The letters B are per se of novel formation. That is, the same gradually increase in thickness from the street casing edge thereof to the base edge thereof. In other words, counterfacing walls of the letters, and exposed surfaces, slope in a tapered or divergent relation from the outer street facing edge to the base edge, in order that the letters at the base portions thereof are securely anchored against displacement from the frame or slab C.

The frame or slab C has the outer face thereof paneled or recessed at 15, over that portion upon which the letters B are exposed. That is to say, the margins of the slab or frame C project beyond the plane of the 75 spaced portion of the said slab on which the letters are exposed, as is clearly shown in Figure 2 of the drawings, and elsewhere, as will subsequently appear in describing the manner of molding or precasting the slab. 80 The slab C is pre-cast of cementitious material, although it may be formed of any approved material, and the same is shaped to insure a permanent anchorage in the wall or curbing D. Its side surfaces and the top and bottom surface are divergent from the outer face of the slab C towards the base thereof. In other words, the slab increases in length and width from the outer face towards the inner face, being substantially in the form of 95 100

a trapezoid whose non-parallel sides are divergent at equal angles from the face of the slab. The slab C is cast into the cementitious curbing or wall D and permanently held therein.

There are several ways by which the improved marker may be assembled. In the first method of constructing the marker, the letters B are precast from cementitious material, and then assembled in their definite relation within a mold wherein the cementitious material is poured to form the slab C. The pre-cast letters B may be made in conventional manner, that is, by using a pattern letter made preferably from aluminum or the like, and from which a mold is made in sand, as is done in ordinary foundry work, and the cementitious or other molten material then poured in the sand and taken out when hardened and to be subsequently placed in the slab material of the concrete marker. The material of the pre-cast letters B is preferably plaster of paris, white cement, or any material which contrasts in appearance and color with respect to the material of which the slab C is formed.

In the preferred manner of forming the pre-cast letters B, the metal mold F of Figures 3, 4 and 5 is provided, which includes a base 20, preferably of aluminum or other metal, having certain portions 21 arising from the upper surface 22 thereof to assist in the formation of the letter to be cast. The base 20 is preferably provided with dowel projections 23 at opposite sides thereof, and adapted to fit into suitable sockets provided inwardly from the under surface of detachable side walls 24 and 25 forming the mold. The side walls 24 and 25 are of course of the same material as the base 20, and the inside surfaces 26 thereof are shaped to conform to the letter which is being cast. Detachable top and bottom walls 27 and 28, are provided, having suitable dowel extensions 29 for fitting into dowel sockets provided in the end surfaces of the mold walls 24 and 25, as shown in Figure 4. The walls 27 and 28 are detachable from the base 20 and from the side walls 24 and 25, and are held centered on the base with respect to the side walls 24 and 25 by the dowel extensions 29. The end walls 27 and 28 of the mold F may be held in place by a suitable clamp K. The cementitious material is then poured into the thus assembled mold F and leveled off at the top thereof in any approved manner, and the pre-cast letter is thus permitted to harden. The particular mold shown in Figures 3 to 5 of the drawings will pre-cast the letter "A", and it is to be noted from Figure 5 that the inside facing walls of the mold converge downwardly, to taper the thickness of the letter from the top of the mold with a gradually decreasing thickness to the bottom surface 22 of the

mold. The inside surfaces of the side walls 24 and 25 are likewise tapered.

The mold L for casting the slab or frame C is of novel formation, including upstanding walls 35, and a bottom 36. The inside surfaces 37 of the walls 35 slope inwardly and downwardly in a converging relation. The bottom 36 is provided with an inside marginal groove 39 peripherally surrounding the inside of the mold at the base of the wall surfaces 37, and thus providing a central raised portion 40 on the bottom of the mold which forms the inset face of the pre-cast slab or frame C, as shown at 15 in Figure 2 of the drawings. The mold L at opposite side walls is provided with upwardly extending lugs 41 to which the ends 42 of a transverse bar 44 are bolted at 45 in a detachable relation. The transverse bar 44 extends across the top of the mold, and is provided with screw threaded openings 46 therein for adjustably receiving clamping screws 48. Prior to the assemblage of the bar 44, in this position, the pre-cast letters B are positioned in properly spaced relation inside of the mold L, and clamped in position upon the bottom 36 by means of the members 48, as is shown in Figure 6 of the drawings. When so positioned, the cementitious material to form the slab C is poured in a fluid condition into the mold L and allowed to settle and is then leveled off flush with the exposed surfaces of the pre-cast letters B, and allowed to harden. The cementitious material forming the slab C is of any approved nature, contrasting in color with the color of the pre-cast letters B, for an obvious purpose. When in the mold the exposed surfaces of the letters B and slab C represent the back of the marker A. The slab C, as thus formed, has the marginal edges thereof sloping in a divergent relation from the countersunk face thereof to the back surface of the slab, as is readily apparent from Figure 6.

When assembled in the wall or curbing D, the marker A, which is now entirely pre-cast, is supported in any suitable relation in the proper position which it will maintain in the curbing, and the material of the wall or curbing D, which is preferably cementitious, is then poured, and the outer face 49 of the curb is flush with the outer surface of the marginal rib which extends about the face of the marker, so that the countersunk face portion of the marker in which the letters appear, will set inwardly a proper distance from the outer face of the wall or curbing D, as a protection. When thus assembled, the marker A has the letters B permanently secured against liability of detachment from the slab C, and the marker slab C is itself permanently dove-tailed or set into the material of the wall or curbing D, against liability of any detachment or working loose.

According to the other method of forming

the marker A, illustrated in Figures 7 to 10 of the drawings, the slab C is first pre-cast with pockets therein for subsequently receiving the material of the letters B which is then poured into the pockets in the slab, and allowed to harden. Under these conditions pattern letters M are used, having the same shape and characteristics of the pre-cast letters B above described, and they are properly positioned on the bottom 36 of the mold L, as shown in Figure 7 of the drawings, and the clamping screws 48 of the mold are then screwed or clamped downwardly upon the pattern letters M; the latter preferably being provided with screw threaded sockets 49^a therein to permit insertion of the screw threaded shanks of the members 48, to prevent any transverse shift of the pattern letters M when the material of the slab is poured. When the pattern letters M are properly positioned and held in place the material of the slab is poured and leveled off, and allowed to harden, as shown in Figure 8. The pattern letters M may then be easily withdrawn, as the same have been greased or otherwise rendered suitable for withdrawal from the material of the slab C when it has hardened, and the pockets 51 are then left in the thus hardened slab C, wherein the material to form the letters B is then poured, as shown at 52 in Figure 10 of the drawings, and allowed to harden. The letters B' on the slab C thus formed, as shown in Figures 7 to 10 of the drawings, are of course of contrasting color, preferably of a cementitious nature.

From the foregoing description of this invention it is apparent that a novel type of street marker has been provided, which is of such a nature as to be efficiently and durably applied to curbing and walls in a manner and by means which will prevent its accidental loosening or becoming detached, and which will meet the ornamental and artistic requirements imposed by various municipal art commissions.

Various changes in the shape, size, and arrangement of parts, may be made to the forms of invention shown, without departing from the spirit of the invention or the scope of the claims.

I claim:

1. In a street marker the combination with a curb having the upright street facing surface thereof provided with a pocket spaced from and entirely below the top of said curb, the pocket having the counter facing surfaces thereof relatively divergent from the outer face of the curbing to the bottom of the pocket, a slab dove-tailed in snug fitting relation within said pocket, said slab having a countersunk face, said slab inwardly of the countersunk face having pockets therein, the counter facing surfaces of said last mentioned pockets being relatively divergent

from the countersunk face, and contrasting characters snug fitting and dove-tailed permanently in said pockets of the slab with the faces of said characters exposed in flush relation on the countersunk face of the slab.

2. In a street marker construction, the combination with a cementitious curb having the upright street facing surface thereof provided with a pocket spaced from and entirely below the top surfacing of said curb, the said pocket being of horizontally elongated substantially rectangular appearance from the front thereof and having the counter facing surfaces therein relatively divergent from the street facing surface of the curb to the bottom of the pocket, a precast cementitious block dove-tailed in snug fitting locked relation within said pocket, said block having a countersunk street facing surface surrounded by a marginal border rib thereabout, so arranged in the pocket that the outer facing surface of the border rib will lie flush with the street facing surface of the curb, with the countersunk face lying inwardly of the street facing surface of both the curb and border rib in a protected relation, said block through the entire thickness thereof and outletting upon the countersunk face having openings, the counter facing surfaces of said openings last mentioned being relatively divergent from the countersunk face to the bottom of said first mentioned pocket, and contrasting cementitious characters snug fitting and dove-tailed in a permanently set relation in said openings of the block, with the street facing surfaces of said characters exposed in flush relation with the countersunk face of the block.
